UNITED STATES PATENT OFFICE.

CLARENCE A. BRADLEY, OF BEATRICE, NEBRASKA.

ANTISEPTIC-CABINET.

SPECIFICATION forming part of Letters Patent No. 624,747, dated May 9, 1899.

Application filed March 3, 1898. Serial No. 672,383. (No model.)

To all whom it may concern:

Be it known that I, CLARENCE A. BRADLEY, a citizen of the United States, residing at Beatrice, in the county of Gage and State of Nebraska, have invented certain new and useful Improvements in Antiseptic-Cabinets; and I do hereby declare the following to be a full, clear, and exact description of the invention, such as will enable others skilled in the art to which it appertains to make and use the same.

My invention relates to a convenient and ornamental cabinet for use by barbers, dentists, and physicians for the purpose of thoroughly and reliably disinfecting their implements.

The spread of diseases, many of which are formidable in their nature and eradicated, if at all, with great difficulty, are, as is well known by physicians and others, many times caused by razors, lather-brushes, and cups in the barbers' trade and in the professions by surgical implements exposed to the infectious diseases and subsequently, without being properly cleaned and disinfected, used upon others.

The object of my invention is to obviate this danger to society by providing a disinfecting-cabinet conveniently constructed and arranged so as to receive such implements or instruments as I have mentioned and thoroughly and efficiently treat the same so as to disinfect them, destroying all microbes and rendering them fit for subsequent use without danger of transmitting any infectious disease whatever from one subject to another.

Various other objects of less importance will hereinafter appear, and the novel features of the invention will be particularly pointed out in the claims.

Referring to the drawings, Figure 1 is a transverse sectional view of my invention, the section being taken on the dotted line 1 2 of Fig. 3. Fig. 2 is a similar view taken on the line 7 8 in either Fig. 3 or 4. Fig. 3 is a vertical sectional view taken on line 5 6 of Fig. 1. Fig. 4 is a similar view on the line 3 4 of Fig. 2. Fig. 5 is a fragmentary sectional view of a portion of the razor or instrument compartment, illustrating in elevation one of the razor-holders. Fig. 6 is a similar view illustrating the razor-holder in plan. Fig. 7 is a cross-section through a series of said holders. Fig. 8 is a view illustrating in elevation the yielding closures employed in front

of each razor-holder. Figs. 9, 10, and 12 are details of construction hereinafter referred to. Fig. 11 is a detail of the heating and radiating drum. Figs. 13 and 14 are details in elevation and section, respectively, of the antiseptic-evaporator. Fig. 15 is a front elevation of the cabinet. Fig. 16 is a vertical longitudinal section of the same.

Similar letters of reference indicate similar parts throughout the drawings.

In practice I preferably form the cabinet shell or casing A' of cast-iron or other metal or wood. The cabinet may be given any desired design, and may have removable front or back walls A², if desired, to give access to the interior.

The structure I will now describe, it will be understood, is located in the outer casing or cabinet and may be spaced therefrom to make room for a surrounding packing of asbestos or other heat-non-conducting material.

The inner shell A³, preferably of sheet-iron, is rectangular and therefore approximates the shape of the external shell or cabinet and may be provided with air-holes G. Located within the same upon its bottom and at its center is a double heating-drum, consisting of an inner cylinder B and an outer cylinder E, the two having an intermediate circulating space. The drum communicates with the exterior by an inclosed opening or passage E', which leads to a corresponding door E², formed in the front wall of the cabinet A'. The bottom of the inner cylinder B may be provided with an opening A, through which any artificial heating means may be provided—as, for instance, a lamp, gas, electricity, &c. In the upper end of the inner cylinder I locate escape vents or holes C, similar holes being formed in the external cylinder E near its bottom and top and indicated, respectively, as D and I. Cold air entering holes I will, upon being heated, rise and be forced through the openings D subsequent to a commingling with the heated air generated in the internal drum and escaping therefrom through the vents C. Surrounding the heating-drum thus described and located in the four corners of the inner shell are the corner compartments H, the same being formed by means of vertical perforated partitions H'.

By these compartments there are formed intermediate the same radial compartments H², with which the heating-drum communicates. The several compartments

being utilized as places of deposit for numerous articles incident to the trade or profession are of course provided with openings that are coincident with doors provided in the cabinet

5 A'. Surmounting the heating-drum and those four intermediate compartments H² is the X-shaped water-tank F, the same having cocks or faucets Z at its four ends, by which warm water may be conveniently drawn at any of 10 the four sides of the cabinet. The tank may be supplied with a proper supply of water in any well-known automatic manner or by pouring the same therein through an inlet-opening m, having a perforated lid n, through 15 which the steam generated in the tank may escape. In order that the level of the water in the tank may be accurately maintained, I may locate adjacent thereto an ordinary sight-tube or water-gage f''.

20 Supported above the water-tank F and having its bottom combining with the roof or top of the tank to form an intermediate heat-radiating space L is located a hot-air sterilizing and disinfecting compartment N, which occupies the whole horizontal area of the inner shell A³ and which may be subdivided at one end by a vertical partition n² to produce a compartment M, both compartments having removable panels or walls whereby convenient access may be obtained. The hot-air compartment N has formed at its top a transversely-disposed dome N', which extends to the top of the inner shell and may be provided at opposite ends with air-vents e. A socket g

35 may be formed in the bottom of the compartment N, and I may seat therein a thermometer o, (see dotted lines, Fig. 3,) which may project through the tops of both cases, so as to be exposed to view, whereby the degree of heat in 40 the compartments N and M can always be observed. The formation of this dome produces at opposite sides thereof what I term for convenience "cool-air" compartments O O, and the same are accessible through outwardly-opening doors a' a'. Corresponding doors a are located in the walls of the dome N', and the doors of each set or side are loosely connected by means of connecting-rods b, located at intervals and loosely connected or coupled 50 at their ends to staples s, located in the adjacent sides of the doors a and a'. It will thus be seen that by opening either of the doors a' the companion door a will be likewise opened.

55 In each of the doors a is formed a plurality of small openings d', in rear of each of which there may be hinged by spring-hinges d² downwardly-opening flaps e. The fronts of these openings may be automatically closed by divided spring-actuated felt-covered clasps d.

Within the dome N' are located in the present instance a series of transversely-disposed razor-holders f, the walls j' of which are convexed and otherwise formed to approximate 60 the shape of a razor-blade, but yet not to contact with the edge thereof. Of course the cabinet I have described is primarily intend-

ed for barbers' use, and hence I have employed razor-holders, it being understood that such interior arrangement is subject to such 70 changes as may be found necessary and will therefore be dictated by the business or profession in connection with which it is to be used.

Located in the hot-air compartment N, immediately under the dome N', is an antiseptic-evaporator B'. (Best illustrated in Figs. 13 and 14.) A simple form of antiseptic-evaporator and one herein employed consists of a metal cylinder B², provided near its upper 80 open end with an annular shoulder c². Upon this shoulder c² and also in the bottom of the receptacle-cylinder I prefer to locate absorbent pads a⁴, preferably of asbestos, the same being thoroughly saturated with any powerful 85 antiseptic liquid. A removable screw-cap d³ is located on the upper end of the receptacle, and the same is perforated, as at c⁴, to emit the fumes of the antiseptic.

90 It will be observed that the heated air rises and passes around the sides of the water-tank, raising the temperature of the body of water to from 180° to 212° Fahrenheit. The heated air then enters the space L, which communicates with compartments H, heating 95 by radiation the compartments M and N, thus assisting in the disinfecting process of such articles as razors and instruments that may occupy the razor-holders f or other forms of racks or supports located in the dome N'. At 100 the same time the evaporator B' will disseminate throughout the chambers M and N the fumes of some powerful germicide—such, for instance, as formaldehyde, forty-per-cent. solution, and alcohol. In the present instance 105 after the doors a' a' are opened the razors are inserted in an open condition, with the toe of the blade in advance, into the holders f, the gates c yielding thereto, after which the doors a' a' are closed, the clasps d closing about the 110 shanks of the razors, thus preventing the escape of the disinfected hot air from the dome N'.

115 The compartments H and H' may be utilized for various useful purposes in line with this invention—as, for instance, in the present case one compartment may be utilized to contain a bowl or receiver containing an antiseptic liquid to be used as a razor-dip, another to receive a bowl containing hot borated 120 soap and water, a third a tray containing an antiseptic fluid to be used as a dip for hair-brushes and combs, and another a bowl containing borated water for cleansing and disinfecting the lather-brush, and so on, each 125 compartment being utilized as desired.

130 From the foregoing it will be apparent that I have attained all of the various objects of my invention and produce a most useful and convenient apparatus for use by barbers, surgeons, and dentists in which to thoroughly cleanse their tools and instruments and render them absolutely free from all disease germs. To get the best results, I prefer wiping

the razor or instrument after use with a cotton cloth which has been previously sterilized by boiling, dried, and treated with a five-per-cent. solution borated, then plunging 5 the same into soapy water heated to a sterilizing-point of 180° Fahrenheit, or even higher, and containing a certain per cent. of soda borate, then dipping it into a solution containing an antiseptic—as, for instance, to a 10 fluid ounce each a certain per cent. of eucalyptus, menthol, boracic acid, fluid extract wild indigo, formaldehyde, forty per cent., alcohol, and water—and thence into the hot chamber, where it is subjected to the foregoing further 15 antiseptic treatment—to wit, hot air of a temperature of about 150° to 180° Fahrenheit or higher and to the evaporation of formaldehyde, forty-per-cent. solution, and alcohol by slow evaporation, or by generation and evaporation 20 of formaldehyde, as hereinbefore described.

What I claim as new is—

1. In a disinfecting apparatus, the combination with a case, of a hot-air disinfecting-chamber located therein and contracted at 25 its top to form a transverse dome, means for heating the same, a cold-air compartment located opposite said dome and above the disinfecting-chamber, and a door between the 30 same and receptacle.

2. In a disinfecting apparatus, the combination with a case, of a disinfecting-chamber located therein and provided with a door, a compartment located adjacent to the chamber 35 and adapted to communicate therewith and provided with a door, and means for actuating the door of the chamber connected to the door of the compartment.

3. In a disinfecting apparatus, the combination with a case, of a disinfecting-chamber provided with a door, a compartment located adjacent thereto and adapted to communicate therewith, and provided with a door, and rods 45 loosely connecting the adjacent sides of the said doors, whereby they may be simultaneously operated.

4. In a disinfecting apparatus, the combination with a case, of a disinfecting-chamber located therein, a door for the same having a 50 series of openings, devices for automatically closing each opening, and implement-holders located in the chamber in line with the openings in the door.

5. In a disinfecting apparatus, the combination with a case, of a disinfecting-chamber located therein, a door having a series of openings, and yielding closures for said openings adapted to fit the shanks of the instruments.

6. In a disinfecting apparatus, the combination with a disinfecting-chamber, provided with a series of openings in its wall, of spring-closures 60 *d*, substantially as specified.

7. In a disinfecting apparatus, the combination with a disinfecting-chamber provided 65 with a series of openings in one of its walls, of spring-actuated gates located in rear of said openings from which side they are adapted to

close the same, and a series of yielding closures in front of each of said openings.

8. In a disinfecting apparatus, the combination with a disinfecting-chamber having a door provided with openings, of a compartment provided with a door and adapted to communicate with the receptacle, means for simultaneously operating both doors, and divided closures for the openings of the door of the receptacle. 70 75

9. In a disinfecting apparatus, the combination with a disinfecting-chamber having a series of openings in one of its walls, of the razor-holders, *f*, alining with the openings, and divided spring-actuated clasps located over the openings and adapted to grasp the shanks of the razors. 80

10. In a disinfecting apparatus, the combination with a case, of a water-tank *F* located therein and combining with the wall of the cabinet to form vertical side heat-passages *H*, means for heating the tank, a superimposed hot-air chamber having a transverse dome 90 formed in its top, the floor of the heating-tank combining with the top of the water-tank to form an intermediate space communicating with the said heat-passages, implement-supports located therein, and doors leading to 95 said dome.

11. In a disinfecting apparatus, the combination with a case, of a disinfecting-chamber located therein and provided in its top with a transverse dome of reduced width having entrances 100 at its longitudinal sides and opposite parallel compartments adapted to communicate therewith and produced by the reduced dome, and provided with doors.

12. In a disinfecting apparatus, the combination with a case, of an X-shaped water-tank located therein, means for heating the tank, and hot-air passages produced between the same and case, a superimposed disinfecting-chamber spaced from the tank and forming a 110 hot-air space communicating with the hot-air passages, and cold-air chambers located at opposite sides of the disinfecting-chamber and normally out of communication with the same. 105

13. In a disinfecting apparatus, the combination with the case, the heating-drum consisting of the inner drum, *B*, having openings, *C*, in its top, and the hooded entrance, *E'*, and the outer drum, *E*, having the lower openings, *I*, and upper openings, *D*, and a superimposed 120 hot-air disinfecting-chamber. 115

14. The combination with the rectangular case, *A'*, the heating-drum, and perforated partitions, *H'*, arranged as shown and producing the compartments, *H²*, *H²*, of the superimposed water-tank, *F*, hot-air disinfecting-chambers, *N*, *M*, the intermediate wall, *N²*, the dome, *N'*, and opposite chambers, *O*, *O*. 125

In testimony whereof I affix my signature in the presence of two witnesses.

CLARENCE A. BRADLEY.
